United States Patent Office

Des. 189,481
Patented Dec. 27, 1960

189,481

EXERCISER OR SIMILAR ARTICLE

Richard J. Harwood, Wichita, Kans., assignor to
Exer-matic, Inc., Wichita, Kans.

Filed May 2, 1960, Ser. No. 60,407

Term of patent 14 years

(Cl. D34—5)

FIG. 1

FIG. 2

FIG. 3

FIG. 4

Fig. 1 is a side elevation view of an exerciser, showing my new design.

Fig. 2 is a front elevation view of same.

Fig. 3 is a top view of same.

Fig. 4 is a rear view of same.

The side opposite to that of Fig. 1 is the same in appearance.

I claim:

The ornamental design for an exerciser or similar article, as shown and described.
